L. S. TIGH.

BELT SHIFTER.

APPLICATION FILED NOV. 21, 1913.

Patented July 7, 1914

UNITED STATES PATENT OFFICE.

LIGH S. TIGH, OF HOBOKEN, NEW JERSEY.

BELT-SHIFTER.

1,102,612.

Specification of Letters Patent.

Patented July 7, 1914.

Application filed November 21, 1913. Serial No. 802,207.

To all whom it may concern:

Be it known that I, LIGH S. TIGH, a citizen of the Republic of China, residing at Hoboken, in the county of Hudson and State of New Jersey, have invented a certain new and useful Improvement in Belt-Shifters, of which the following is a specification.

The invention relates to that class of washing machines in which the articles of clothing or other material to be laundered are contained in a cylinder rotatably mounted in a tank, with means for rotating such cylinder alternately in opposite directions, and the object of the invention is to provide simple, reliable mechanism for effecting such alternate rotation.

The invention consists in certain novel features and details of construction and arrangement by which the above object is attained, to be hereinafter described and claimed.

The accompanying drawings form a part of this specification and show the invention as it has been carried out in practice.

Figure 1 is an end elevation of the improved washing machine, with certain portions broken away, and partly in vertical section. Fig. 2 is a corresponding side elevation. Fig. 3 is a horizontal section through the frame of the machine below the tank, showing the driving means in plan view. Fig. 4 is a transverse section and elevation of the belt-shifter mechanism alone. Fig. 5 is a corresponding plan view. Fig. 6 is a transverse section through a portion of the belt-shifting mechanism, on a larger scale.

Similar letters of reference indicate the same parts in all the figures.

A is the tank, rectangular in plan view, having a semicylindrical bottom A¹, and supported on vertical legs or standards A² preferably of angle iron. The tank is adapted to contain water and is equipped with the usual inlet and discharge pipes therefor, not shown. Within the tank A is a perforated washing cylinder B mounted horizontally in suitable bearings and having a trunnion B¹ projecting at one end, through which the cylinder may be rotated by the engagement of a loose sprocket-wheel B² with such trunnion, the engagement being effected by a clutch B³ operated by a lever B⁴. Beneath the tank A and inclosed within the angles of the standards A² is a base

C on which is mounted the driving mechanism.

D is a transverse driving-shaft mounted in suitable bearings at one end of the base, rotated continuously in one direction by an electric motor, as indicated at M, or by any preferred power, carrying four pulleys D¹ D² and D³ D⁴ arranged in pairs and fast thereon. At the opposite end of the base is a driven shaft E carrying four pulleys E¹ E² and E³ E⁴ corresponding to those on the drive-shaft D but with one of each pair, E¹ and E⁴ loosely mounted. An open driving belt F communicates motion from the pair D², D⁴ to E³, E⁴, and a crossed belt G from D¹, D² to E¹, E², rotating the shaft E in either direction, depending upon which of the belts is engaged with the fast pulleys E² or E³ thereon. The shaft E carries a worm E⁵ in mesh with a wormwheel H¹ on a horizontal shaft H arranged at a right angle to and above the shaft E. On the outer overhung end of the shaft H is a sprocket-wheel H² connecting through a sprocket chain H³ with the sprocket-wheel B² on the cylinder-shaft or trunnion B¹. It is obvious that the worm E⁵ will be rotated in opposite directions accordingly as it is driven by the open belt F or crossed belt G, and the cylinder B correspondingly rotated in one direction or the other. This change in direction is effected by shifting the belts at intervals.

J is a shifter-bar having downwardly projecting pins J¹ J² in engagement with the belts near the shaft D, and slidably mounted in a support or guide J³ fixed upon a frame J⁴ on the base C. On the bar is a head J⁵ having grooves j on its upper and lower faces which receive lips J⁶ on the support J³ and serves with the inclosed portion of the bar to guide the latter in its endwise shifting motions. A pin J⁷ projects from the lower face of the head into the path of an oscillating crank L² adapted to strike such pin alternately on opposite sides and thus shift the belts. The shaft H is supported at one end in a casing H⁴ for the worm gear and at the other in a bearing H⁵ in the frame H⁶, and on the inner overhung end is a small pinion H⁷ in mesh with a gear-wheel L¹ on a shaft L located below and parallel with the shaft H, having its bearings in the frames H⁶ and J⁴ and carrying the crank or finger L² above described.

When the worm-shaft E is driven by the

open belt the shaft L is turned in one direction until the crank L² through contact with the pin J⁷ throws the shifter to put the cross-belt in action and correspondingly induces an immediate reversal in direction of rotation of the shafts E and L and of the cylinder B, which reverse rotation continues during the interval required for the slowly moving crank L² to traverse its long lower arc and rise to strike the pin J⁷ on the opposite side and again move the belts to put the open belt into service, thus producing the desired alternate changes in direction of rotation of the cylinder B. The duration of rotation in either direction depends upon the relative proportions of the pinion H⁷ and gear-wheel L¹.

On the guide J³ is a centrally located fixed stud J⁹ and J⁸ is a similar stud at the mid-length of the head J⁶ and forming an upright extension of the pin J⁷. The studs serve as abutments for the end of a flat semicircular spring N exerting its force to separate the studs and serving to induce a rapid completion of the endwise movement of the shifter-bar J when the pin J⁷ and stud J⁸ are forced by the crank L² past the center line of the stud J⁹ in either direction and thus insure a complete and quick transference of the belts in making the reversal and permitting the crank L² to begin its travel in the opposite direction.

S is a rod fastened stiffly to the shifter-bar J and extending parallel with the cross-belt G. At its free end it carries a downwardly projecting pin S¹ adapted to engage the belt beyond the crossing point and facilitate the movement in shifting to the idle pulley E¹. It is supported by an arm H⁸ extended from the frame H⁶.

On the outer end of the shaft H adjacent to and beyond the sprocket-wheel H² is a small loosely mounted sprocket-wheel R, adapted to rotate with the shaft by the engagement of a clutch R¹, over which runs a sprocket chain R² serving to rotate a sprocket-wheel R³ fixed on the shaft R⁴ of a wringer R⁵ and operate the latter when required. The clutches B³ and R¹ permit the cylinder and wringer to be operated independently, and the crank L² is slidably mounted on the shaft L so that it may be drawn back out of the line of contact with the pin J⁷ to permit the wringer R⁵ to be turned continuously in the proper direction, or to permit the cylinder B to rotate in either direction continuously if desired.

A³ is a removable cover for the tank, preferably hinged along the center line as at A⁴ to permit access to the interior without complete removal of the cover.

The driving and reversing mechanism is simple, strong, and reliable, and well adapted for service under the conditions usually obtaining in situations in which ma-

chinery of this class is installed and operated.

I claim:—

1. In an apparatus of the character set forth, a drive shaft and a driven shaft, fast and loose pulleys on said shafts, arranged in pairs and carrying open and crossed belts, a belt-shifter engaged with said belts, a guide in which said belt-shifter is slidably mounted, means actuated by said driven shaft for moving said belt-shifter alternately in opposite directions and correspondingly changing the direction of rotation of said driven shaft, a stud fixed on said guide, a stud on said belt-shifter, a spring carried by said studs and tending to separate the latter, said spring arranged to accelerate and complete the movement of said belt-shifter in either direction by the movement of such shifter-stud in the same direction past said fixed stud, and connections from said driven shaft to a rotatable member.

2. In an apparatus of the character set forth, a drive shaft and a driven shaft, fast and loose pulleys on said shafts, arranged in pairs and carrying open and crossed belts, a belt-shifter engaged with said belts, a pin on said belt-shifter, a worm on said driven shaft, a wormwheel driven by said worm, a wormwheel shaft, a pinion thereon, a gear-wheel in mesh with said pinion, a shaft for said gear-wheel, a crank slidably mounted on such gearwheel shaft arranged to strike said pin and shift said belt-shifter alternately in opposite directions, and thereby reverse the direction of rotation of said wormwheel-shaft, connections from the latter to a rotatable member, said crank arranged to be moved out of the line of contact with said pin and permit said driven shaft to be rotated continuously in one direction.

3. In an apparatus of the character set forth, a drive shaft and a driven shaft, fast and loose pulleys on said shafts arranged in pairs and carrying open and crossed belts, a worm upon the driven shaft, a shaft at right angles to and above said driven shaft, a worm wheel thereon engaging said worm, a shifter-bar having downwardly projecting pins in engagement with said belts near the driving shaft, a guide in which said shifter-bar is slidably mounted, a head on said bar having grooves on its upper and lower faces, lips on said guide received in said grooves, a pin projecting from the lower face of said head, and an oscillating crank movable in the path of said last-named pin.

4. In an apparatus of the character set forth, a drive shaft and a driven shaft, fast and loose pulleys on said shafts arranged in pairs and carrying open and crossed belts, a worm upon the driven shaft, a shaft at

right angles to and above said driven shaft, a worm wheel thereon engaging said worm, a shifter-bar having downwardly projecting pins in engagement with said belts near the 5 driving shaft, a guide in which said shifter-bar is slidably mounted, a head on said bar having grooves on its upper and lower faces, lips on said guide received in said grooves, a pin projecting from the lower face of said 10 head, an oscillating crank movable in the path of said last-named pin, a stud fixed centrally on said guide, a stud at substan-

tially the midlength of the head and forming an upright extension of said last-named pin, and a flat substantially semi-circular 15 spring exerting its force to separate said studs.

In testimony that I claim the invention above set forth I affix my signature, in presence of two witnesses.

LIGH S. TIGH.
